UNITED STATES PATENT OFFICE.

BERTHOLD PIROSH, OF CHICAGO, ILLINOIS.

PERPETUAL-REMINDER SYSTEM.

SPECIFICATION forming part of Letters Patent No. 704,100, dated July 8, 1902.

Application filed February 28, 1902. Serial No. 96,092. (No model.)

To all whom it may concern:

Be it known that I, BERTHOLD PIROSH, a citizen of the United States, residing at Chicago, in the county of Cook and State of Illinois, 5 have invented certain new and useful Improvements in Perpetual-Reminder Systems, of which the following is a specification.

My invention relates to improvements in a system of and appliances for keeping in convenient form and in such a manner as to be called to the attention of the user at the proper time reminders of various kinds; and my invention is especially adapted for the use of those who frequently have successive 15 transactions with the same person.

A particular object of my invention is to provide a filing or memorandum system which shall be compact, convenient, simple, and reliable. These and such other advantages as 20 may appear are attained by the use of the system hereinafter described in connection with the appliances shown in the accompanying drawings, in which—

Figure 1 is a plan view of a pocket filing 25 or memorandum case. Fig. 2 is a perspective view of the same folded in convenient form to be put in a vest-pocket. Fig. 3 shows one side of a card for use in connection with such memorandum-case, and Fig. 4 shows the opposite side of the same card.

The filing-case comprises a series of pockets consisting of one for each day of any given period or cycle of time, which is repeated at fixed intervals. The filing-case shown in the 35 drawings is prepared for use in connection with periods or cycles of one week, each pocket indicating one day of the week and being correspondingly lettered or marked. The principle of my system and devices, however, is adaptable for use in connection with periods of varying length, such as weekly, monthly, quarterly, or the like; but it will be found that periods of one week form the most convenient basis upon which to operate. A filing-case containing one pocket or receptacle 40 for each such period may be made in any suitable shape or form; but I prefer constructing it as shown in the drawings, in which it consists of a flexible back, to which are attached 45 the pockets, so that the case may be folded or

rolled in small compass, as shown in Fig. 2, and conveniently carried in the user's pocket.

In connection with the filing-case I use reminder-cards, upon one side of which are indicated the days of the month from "1" to 55 "31," inclusive, and preferably also blanks for inserting any given year or month. Upon the opposite side may be arranged convenient blanks for the name, address, &c., of any person. A convenient form is shown in Fig. 3, 60 in which blanks are provided for the name, address, and telephone-number of a caller and for the hour at which he called, this form of card being especially for use by a physician's office-attendant for noting calls made 65 during the physician's absence.

For a physician's practice, for instance, my improved appliances would be used as follows: Assuming that a patient sends a call for the physician during his absence, an attendant notes all desired information on one face of a card, such as shown in Fig. 3, and puts it aside until the physician reaches his office. The physician then puts the card in the pocket for that day, and upon making his 70 round of calls he is reminded by the cards in that pocket of all patients upon whom he should call that day. Having reached the patient's house and made the call, he crosses from the back of the card, as shown in Fig. 80 4, the day of the month upon which the call was made, thereby having a convenient memorandum of calls made, and if he is to call again upon another day—say the following Monday—he puts the card in the pocket for 85 Monday and need give the matter no further thought until when Monday arrives he looks through the cards in that pocket to see with whom he has appointments for that day. If, however, his next call is to be made more 90 than a week later, he first checks or otherwise indicates upon the back of the card the day of the month upon which such next call is to be made, and then puts the memorandum-card into the pocket indicating the day of the 95 week upon which that day of the month will fall. When next he examines that pocket, he finds on reference to the back thereof that his next call on that particular patient is not due until some later week, and the card is re- 100

turned to its pocket and no further attention paid thereto until the next week rolls around.

From the foregoing explanation it is evident that it is possible with my system and appliances to keep track of practically an indefinite number of appointments with the same person in rotation by means of suitable check-marks after a card has once been made out for that person, although for practical purposes it will be often found that a card bearing the data (shown in Figs. 3 and 4) will answer all requirements, and cards with even less data can be used satisfactorily.

15 While I have explained the use of my system in connection with a physician's practice, it is evident that it is adaptable for use in a wide field wherever successive appointments, payments, letters, calls, or the like are to be made upon the same person or at the same place or in the same connection, and I contemplate such varied uses of my invention, and so do not limit myself to its application to any one line of business.

20 25 Having thus described my invention, what I claim, and desire to secure by Letters Patent, is—

1. A reminder system comprising a series of receptacles, being one receptacle for each 30 unit of time of a recurring cycle, and a plurality of memorandum-blanks adapted to be filed in said receptacles, substantially as described.

2. A reminder system comprising a pocket-case provided with one pocket for each day of a recurring succession of days, and a plurality of reminder-cards adapted to be temporarily filed in any of said pockets, substantially as described.

3. A reminder system comprising a pocket-case provided with one pocket for each day of a recurring succession of days, and a plurality of reminder-cards bearing the figures 1 to 31, inclusive, and having space for memoranda to be written thereon, substantially as described.

4. A reminder system comprising a pocket-case consisting of a flexible back provided on its face with seven pockets, and a plurality of reminder-cards bearing on one face the figures 1 to 31, inclusive, and having on their opposite face space for memoranda to be written thereon, each of said cards being adapted to be filed in each of said pockets in succession, substantially as described.

BERTHOLD PIROSH.
